Patent expires January 5, 1964

9 Claims. (Cl. 250—13)

1

It has already been proposed to simplify the control of a transceiver circuit arrangement, in which the carrier-wave frequency of the transmitter must correspond with the tuning frequency of the receiver, by making the transmitting frequency and the tuning of the receiver correspond automatically with one another by means of a control circuit, which is preferably connected to the receiver and, provided that the transmitting frequency lies within control range determined by the construction of the control circuit, yields a positive or negative control voltage according as to whether the transmitting frequency is higher or lower than the tuning frequency of the receiver.

The control voltage derived from the said control circuit, hereinafter the usual term frequency-discriminator will be used, controls in this case a reactance tube or other control member coupled with the frequency-determining circuit of the transmitter, for example in view of frequency-modulation of the carrier-wave to be transmitted, in such a manner that deviations of the transmitting frequency relatively to the tuning of the receiver are substantially completely made up for.

We have found that during operation of transceiver circuit-arrangements of the aforesaid kind it occurs, however, that the automatic coupling of the transmitting frequency and the tuning of the receiver by means of the frequency discriminator falls out in spite of the fact that the transmitting frequency proves to be steadily and amply within the control range of the frequency discriminator.

According to the invention the said drawback of transceiver circuits of this kind is obviated by temporarily varying the transmitting frequency occurring immediately upon changing over from reception to transmission relatively to the tuning of the receiver.

The invention is based on the recognition that the said drawback ensues from the properties of the discriminator in conjunction with the switching-off of the transmitter during listening to a counterstation, as is necessary with transceivers of the present kind, and with the variation of the transmitting frequency and the tuning of the receiver relatively to one another during this time.

For a better understanding of the invention reference is had to the following detailed description thereof to be read in connection with the accompanying drawing wherein,

Fig. 1 is a graph illustrating the operation of a frequency discriminator incorporated in an embodiment of the invention;

2

Fig. 2 is a schematic diagram of one preferred embodiment of the invention; and

Fig. 3 is a schematic diagram of another preferred embodiment of the invention.

- 5 In Fig. 1 the tuning frequency (ordinate) of, for example, the frequency-determining circuit of a transmitter is represented as a function of the tuning capacity of the circuit, a discriminator bringing the tuning frequency of the circuit as 10 much as possible into an agreement with the tuning frequency ω_0 given by the discriminator. Now if the tuning capacity is varied between two values, for example, of from C_1 to C_6 , lying on either side of the value of C_0 of the tuning capacity corresponding to the frequency ω_0 , the 15 relation between the tuning frequency of the circuit and the tuning capacity can, in principle, be represented by the curve 1, 2, 3, 3', 4, 5, 5', 6. At the points 1, 2 the coupling to be brought about 20 by the discriminator is not yet operative. Only at a capacity value C_3 slightly deviating from C_0 it becomes operative, as a result of which the frequency ω_3 is readjusted to the value of ω_0 which differs only slightly from ω_0 . Upon a further 25 variation (C_4) of the tuning capacity the coupling remains operative up to a capacity value C_5 materially deviating from C_0 , when it falls out, the tuning frequency then beginning to deviate considerably from ω_0 on account of a variation 30 leaping from ω_5 to ω_5' , and the coupling further (C_6) remaining inoperative.

Now if the tuning capacity is varied inversely, i. e. from C_7 to C_{12} , the curve 7, 8, 9, 9', 10, 11, 11', 12 is obtained in an analogous manner as explained before.

- 35 At C_9 the coupling becomes operative, at C_{11} inoperative. The range between C_9 and C_{11} is referred to as the control range of the discriminator, the much smaller range between C_3 and C_5 40 on the contrary as the range of interference of the discriminator. Normally the interference range covers only a fraction of the control range, regardless of the fact whether, for example, a discriminator of the so-called phase-discriminating kind or watch type is used, this fraction being smaller as the control obtained becomes better (for example by using a higher amplification of the control voltage obtained).

Now if at a given moment the transmitter of 50 the arrangement is used and the transmitting frequency is coupled with the tuning frequency of the receiver by the discriminator, and after the transmitter has been cut out for some time with a view to listening to a counter station, the transmitting frequency and the tuning of the receiver,

upon the subsequent changing over from reception to transmission, may have varied with respect to one another, due to temperature fluctuations, mechanical shocks or vibrations or the like to such a degree that there is too great a difference between the two frequencies to be coupled by the discriminator to render coupling inoperative, for it becomes operative only when the transmitting frequency is within the narrow interference range of the discriminator.

Now by temporarily varying, according to the invention, either the transmitting frequency or the tuning frequency of the receiver and/or of the discriminator after changing over from reception to transmission, thus bringing the transmitting frequency into the interference range of the discriminator, the coupling between the transmitting frequency and the tuning frequency of the receiver becomes operative and will remain so even after the said temporary variation, provided only that the transmitting frequency was initially within the control range of the discriminator.

The temporary variations which has to bring the transmitting frequency for a moment within the interference range of the discriminator may, in accordance with time, exhibit inter alia the form of an aperiodic impulse, a damped oscillation or an undamped oscillation occurring for some time and may be brought about in various ways.

For this purpose a reactance tube coupled with the frequency-determining circuit of the transmitter may be used, to whose control a voltage impulse is supplied.

The required voltage impulse may be obtained from the receiver, in which a voltage impulse will occur when the transmitter is switched on abruptly.

It is also possible to connect an auxiliary condenser, which is provided with a flexibly suspended electrode, in parallel with the frequency-determining circuit of the transmitter, this condenser receiving an impetus when changing over from reception to transmission.

A construction of this kind may, however, also become operative by mechanical shocks or vibrations which, of course, is undesirable. It is therefore advisable that the means procuring the required frequency variations should as much as possible be electrical.

It is efficient and simple to make the device for changing over from reception to transmission directly bring about the desired voltage variation.

This again may be effected in various ways.

In order that the invention may be clearly understood and readily carried into effect, it will now be explained more fully with reference to the accompanying drawing, given by way of example, in which Figures 2 and 3 illustrate forms of construction of a device according to the invention pertaining to the last-mentioned category of constructions.

In the transceiver circuit arrangement shown in Fig. 2 the transmitting part is shown on the left, the receiving part on the right of an aerial 13.

The transmitting part comprises an oscillator 14 having a frequency-determining circuit 15 with which a reactance tube 16 is coupled. The oscillations generated and, as the case may be, modulated in frequency by the reactance tube 16, are supplied to the aerial 13 through a power amplification stage 17.

The receiving part arranged for superheterodyne reception comprises a high-frequency pre-

amplification stage 18, a mixing stage 19, a local oscillator 20, an intermediate-frequency amplifier 21, a detector 22 and a low-frequency amplifier 23 to which a loudspeaker 24 is connected.

According as to whether the device represented will be used for transmission or reception the transmitting or receiving part is connected to the aerial 13 by means of a transceiver switch 25. During reception the transmitter is switched off, whereas during transmission the receiver remains switched on, as the case may be with reduced sensitiveness, in view of bringing the transmitting frequency and the tuning of the receiver in agreement with one another, which takes place as follows.

During transmission (switch 25 turned to the left) the transmitted oscillations are also supplied to the receiver through a coupling condenser 26 having a low value. The oscillations picked up by the receiver control a frequency-discriminator 27 connected to the intermediate-frequency receiving part (21); this discriminator produces a positive or a negative control-voltage at an output resistance 28 if the frequency of the incoming oscillations is higher or lower than the tuning frequency of the receiver. The control voltage obtained from the discriminator is introduced with such a polarity into the control grid circuit 30 of the reactance tube 16 of the transmitter connected to a negative bias battery 29 that deviations of the transmitting frequency relatively to the tuning of the receiver are reduced.

In order to render the coupling between transmitting frequency and tuning of the receiver operative according to the invention when switching over from reception to transmission the transceiver switch 25 has coupled to it a switch 31 which completes the charging circuit of a condenser 32 when switching over from reception to transmission. This charging circuit comprises, besides the switch 31, successively a battery 33, the condenser 32 shunted by a leakage resistance 34 and the primary winding of a transformer 35, whose secondary winding is located in the control-grid circuit 30 of the reactance tube 16.

When closing the switch 31 an impulse-like current is set up in the charging circuit of the condenser 32, which produces a positive and a negative impulse successively in the control grid circuit 30, due to which the transmitting frequency sweeps first to the one and then to the other side of the frequency immediately occurring upon changing over from reception to transmission. By a suitable choice of the amplitude of the impulses occurring in the control grid circuit 30 it is achieved that, regardless of the value of the transmitting frequency lying within the control range and outside the interference range of the discriminator, the transmitting frequency, due to the impulses, has for a short time a frequency lying within the interference range, as a result of which the coupling between the transmitting frequency and the tuning of the receiver is brought about.

A similar effect is obtainable by shunting the secondary winding of the transformer 35 by a condenser 36. The resonant circuit thus ensued in the control-grid circuit 30 receives an impetus when closing the switch 31 and produces the appearance of a damped oscillation in the control grid circuit, which causes a corresponding variation of the transmitting frequency.

In both cases set out in detail it is of no im-

portance in what direction the transmitting frequency varied with respect to the tuning of the receiver.

If only a unilateral variation of the transmitting frequency need be taken into account, the form of construction shown may be simplified by including in the grid lead 30 a coil instead of the transformer 35, to which a current impulse can be supplied in an analogous manner as previously supplied to the primary winding of the transformer 35. Thus the current impulse produces in the control grid circuit 30 only an aperiodic impulse having a given polarity which, however, has the desired effect, provided that the polarity of the impulse was chosen in accordance with the variation of the transmitting frequency to be anticipated.

Finally Fig. 3 shows one form of construction of an auxiliary circuit arrangement for the production of two succeeding voltage impulses having an opposite polarity, in which no inductive switching elements, but exclusively resistances and condensers are used.

The auxiliary circuit shown in Fig. 3 is arranged to cooperate with elements 13 to 28 and 30 in Fig. 2, the grid lead 30 for reactance tube 16 being connected serially through discriminator output resistor 28 and through the auxiliary circuit to ground.

The auxiliary circuit shown in Fig. 3 comprises two switches 38 and 39 which are coupled with the transceiver switch 25 and, during reception, are turned downwards. Thus a condenser 40 connected between the grid lead 30 of the reactance tube 16 and earth has supplied to it through resistances 41, 42 and the switch 39 by means of a battery 43, 44, a voltage which is higher, for example two times as high ($-2 V_g$), as the grid bias ($-V_g$) required by the reactance tube 16. At the same time an auxiliary condenser 45 unilaterally earthed by the switch 38 is connected to the battery 43, 44 through the switch 39 and is thus also charged to a voltage of $2 V_g$.

On changing over to transmission the switches 38, 39 are turned upwards and the circuit-arrangement shown in Fig. 3 ensues, in which the normal grid bias (V_g) is supplied by the battery 43 to the condenser 40 through resistance 41, switch 38, condenser with leakage resistance 42 and switch 39.

When operating the switches 38 and 39 the condenser 45 exhibits a charging voltage of $2 V_g$ which becomes operative in the last-mentioned circuit with a polarity opposite to that of the charging voltage of the condenser 40 and of the voltage of the battery 43. Immediately upon changing over from reception to transmission the junction between the resistances 41, 42 will have a potential $+2 V_g - V_g = +V_g$ relatively to earth.

By a suitable choice of the time constant of the discharging circuit of the condenser 45 it can now be achieved that the voltage of the condenser 40, initially being $-2 V_g$, assumes a value between $-V_g$ and 0 or even a positive value shortly after changing over from reception to transmission, whereas the final voltage set up at the condenser 40, after changing over from reception to transmission, will be $-V_g$.

Thus it is achieved, as has been aimed at, that upon changing over from reception to transmission the grid of the reactance tube temporarily receives successively a higher and a lower bias than the required bias, so that the coupling be-

tween receiving and transmitting frequency can steadily become operative.

What I claim is:

1. In combination with a transceiver including a transmitter provided with a tuned circuit for determining the operating frequency thereof, a tunable receiver and means to switch-over from reception to transmission, apparatus for automatically aligning the operating frequency of the transmitter with the frequency to which the receiver is tuned comprising a frequency control device coupled to the tuned circuit of said transmitter and arranged to adjust the frequency thereof in accordance with a control voltage, frequency discriminator means coupled to said receiver to develop a control voltage whose value is a function of the deviation of the transmitter frequency relative to the frequency of the receiver, means to apply said control voltage to said device to effect a corresponding adjustment in the frequency of said transmitter, and means responsive to the switch-over operation in the transceiver to apply momentarily an auxiliary control voltage to said device to swing the frequency of the transmitter into the operating range of said discriminator.
2. In combination with a transceiver including a transmitter provided with a tuned circuit for determining the operating frequency thereof, a tunable receiver and means to switch-over from reception to transmission, apparatus for automatically aligning the operating frequency of the transmitter with the frequency to which the receiver is tuned comprising an electronic frequency control device coupled to the tuned circuit of said transmitter and arranged to adjust the frequency thereof in accordance with a control voltage, a frequency discriminator coupled to said receiver to develop a control voltage whose value is proportional to the deviation of the transmitter frequency relative to the frequency of the receiver within a predetermined range of deviation, means to apply said control voltage to said device to effect a corresponding adjustment in the frequency of said transmitter, and means responsive to the switch-over operation in the transceiver to apply momentarily an auxiliary control voltage to said device to swing the frequency of said transmitter into said range of deviation.
3. A transceiver circuit as set forth in claim 2 wherein said auxiliary control voltage has the form of an aperiodic impulse.
4. A transceiver circuit as set forth in claim 2 wherein said auxiliary control voltage has the form of a damped oscillation.
5. A transceiver circuit as set forth in claim 2 wherein said auxiliary control voltage has the form of an undamped oscillation maintained for a predetermined period.
6. In combination with a transceiver including a transmitter provided with a tuned circuit for determining the operating frequency thereof, a tunable receiver and means to switch-over from reception to transmission, apparatus for automatically aligning the operating frequency of the transmitter with the frequency to which the receiver is tuned comprising a grid-controlled reactance tube coupled to the tuned circuit of said transmitter and arranged to adjust the frequency thereof in accordance with a control voltage applied to the grid of said tube, means to apply a bias voltage to the grid of said tube, a frequency discriminator coupled to said receiver to develop a control voltage whose value is proportional to

7 the deviation of the transmitter frequency relative to the frequency of the receiver within a predetermined range of deviation, means to apply said control voltage to the grid of said tube to effect a corresponding adjustment in the frequency of said transmitter, and means responsive to the switch-over operation in said transceiver for varying momentarily the bias on the grid of said tube to swing the frequency of said transmitter into said range of deviation.

7. In combination with a transceiver including a transmitter provided with a tuned circuit for determining the operating frequency thereof, a tunable receiver and means to switch-over from reception to transmission, apparatus for automatically aligning the operating frequency of the transmitter with the frequency to which the receiver is tuned comprising a grid-controlled reactance tube coupled to the tuned circuit of said transmitter and arranged to adjust the frequency thereof in accordance with a control voltage applied to the grid of said tube, means to apply a bias voltage to the grid of said tube, a frequency discriminator coupled to said receiver to develop a control voltage whose value is proportional to the deviation of the transmitter frequency relative to the frequency of the receiver within a predetermined range of deviation, means to apply said control voltage to the grid of said tube to effect a corresponding adjustment in the frequency of said transmitter, and means responsive to the switch-over operation in said transceiver for varying momentarily the bias on the grid of said tube to swing the frequency of said transmitter into said range of deviation, said last named means including a capacitor, a source of charging voltage for said capacitor, a resistor connected across said capacitor, a transformer having a primary and a secondary, a switch, said capacitor, said source, said primary and said switch being serially connected in a closed circuit and means closing said switch upon the switch-over of said transceiver whereby said capacitor is charged to develop a voltage impulse in said secondary, said voltage impulse being applied to vary the bias on the grid of said tube.

8. An arrangement, as set forth in claim 7, further including a capacitance connected across said secondary to define a resonant circuit.

9. In combination with a transceiver including a transmitter provided with a tuning circuit for

determining the operating frequency thereof, a tuned receiver and means to switch-over from reception to transmission, apparatus for automatically aligning the operating frequency of the transmitter with the frequency to which the receiver is tuned comprising a grid-controlled reactance tube coupled to the tuned circuit of said transmitter and arranged to adjust the frequency thereof in accordance with a control voltage applied to the grid of said tube, a frequency discriminator coupled to said receiver to develop a control voltage whose value is proportional to the deviation of the transmitter frequency from the frequency of the receiver within a predetermined range of deviation, means to apply said control voltage to the grid of said tube to effect a corresponding adjustment in the frequency of said transmitter, and means responsive to the switch-over operation in said transceiver for varying momentarily the bias on the grid of said tube to swing the frequency of said transmitter into said range of deviation, said last named means including a first capacitor, a source of bias voltage connected to said grid, a resistance, a second capacitor, a leakage resistor shunting said second capacitor, means for charging prior to the switch over operation said first and second capacitors in opposite polarity to a voltage which is higher than the voltage of said bias source, and means responsive to the switch-over operation for connecting said first capacitor in series with said resistance and said second capacitor across said bias source.
